David Bruce
Jefferson City Mo
Yours truly
Postscript Oct 22 1863

Des. 1850

David Bruce, of Newtown, New York.
Letters Patent No. 1850-Dated Nov. 17th, 1863.
Design for Letter Press Types.

The schedule referred to in these Letters Patent and making part of the

To all whom it may concern:

Be it known that I, David Bruce,

Dec. 1850

of Newtown, Queens County, State of New York, "Type founder, and letter punch cutter," have invented or produced a new and original design or conformation of the faces of Metal types, for printing the Alphabet, and other purposes, which characterize as the "Jefferson Script" and I do hereby declare the following to be a full description of the same, reference being had to the accompanying specimens or drawings of the same.

The nature of my invention consists in making the faces or letters of a broad or full round shape, with a slight leaning backwards, and having their heavy down stroke or swell, formed at their lower sides, or edges, in contradistinction to the common practice of forming the swell at the middle of the down stroke, so as to give the printed matter the unique, and ornamental appearance of a heavy base, with a vanishing line for their upper sides.

It will be obvious that this peculiar conformation of the faces of the type must harmonize throughout the whole line of printed matter. Each type therefore is but a part of a whole design, which is not complete unless its uniformity is preserved throughout the entire alphabet or other printed matter in the "Jefferson Script" type.

Its peculiarity of design consists in the sameness of the character, limited only in its application by the difference of shape of the several letters of the alphabet, but not in the distinguishing characteristics, of the broad full round letter, backward inclination, and swelling lines of the lower half of the letters, as forming a new and ornamental style of letter press printing.

Having now described my invention, I will

B6

Des. 1850

proceed to set forth what I claim and desire to secure by Letters Patent of the United States.

I claim the production of the new and ornamental style of letter press printing, which I have characterized as the "Jefferson Script," by means of metal types having their faces cut in the form and shape hereinbefore set forth.
